Attorney

UNITED STATES PATENT OFFICE.

HUGH W. SANFORD, OF KNOXVILLE, TENNESSEE.

MINE CAR.

Application filed May 8, 1924. Serial No. 711,885.

My improvement relates particularly to mine cars which are to be turned or tilted bodily forward for the discharge of their contents.

5 The main object of my invention is to produce a mine car which is adapted to be turned or tilted forward for the discharge of its contents, as above stated, and which has its floor or bottom low relative to the 10 track, in order that for a given head room the car will hold a maximum load, and, for the sake of greater stability of the car on the track, carry the load close to the track rails.

To this end, the car comprises a main 15 frame composed of end sills and parallel side sills, a bottom or floor section between said side sills, an auxiliary floor section outside of said frame, axles supported by said side sills, wheels on said axles, and slanting housings for the wheels.

In the accompanying drawings,

Fig. 1 is an elevation of a mine car embodying my improvement, the bottom of the car being especially constructed for tilting 25 the car endwise for dumping its load, portions being broken away;

Fig. 2 is a plan of the car shown by Fig. 1, portions being broken away;

Fig. 3 is an upright, longitudinal section 30 on the line, 3—3, of Fig. 2;

Fig. 4 is an upright, transverse section on the line, 4—4, of Figs. 1 and 3, looking toward the right;

Fig. 5 is an upright, transverse section on the line, 5—5, of Figs. 1 and 3, looking toward the right;

Fig. 6 is an upright, transverse section on the line, 6—6, of Figs. 1 and 3, looking toward the left.

40 As above stated, the form of car shown by the drawings is intended to be tilted forward in a tipple which rotates on an axial line which is transverse to the length of the track. In said drawings, A, A, represent end sills 45 having a bumper, A¹, projecting outward therefrom, a draw bar element, A², also projecting outward from said end sills and located over said bumper, truss members, A³, and corner stiffeners, A⁴ and A⁵, all preferably formed of one integral casting.

The said bumper, A¹, is swelled outward as indicated by the drawing, and immediately over the central portion of the bumper is the aforesaid draw bar element, A², provided with a coupling pin opening, A⁷, which is directly over a similar opening, A⁸, in the

bumper, a space being left between the draw bar, A², and the bumper, A¹, for the reception of a coupling link, the coupling pin being designed to drop through the openings, A⁷ and A⁸.

60 The corner stiffeners, A⁴ and A⁵, which have been described as being part of the integral casting, are to be securely riveted to the longitudinal or side sills, B, B.

65 The side sills, B, B, are to be so heavy as to make them amply strong to resist downward strain or drooping and to resist endwise thrust and also train pull. At the same time, the frame consisting of the side sills 70 and the end sills must possess sufficient flexibility to allow the axles to incline independently of each other, whereby the car wheels at the same side of the car are allowed to assume different levels to conform to variations or irregularities in level of the track 75 on which the car runs.

The two axles, C, are arranged transversely to the side sills and rest in bearings, C¹, secured to the side sills by bolts, C². In 80 the form shown in the drawings, said bearings are applied flatwise to the outer sides of the side sills and extend through the sills. On each end of the axle is a track wheel, W. This arrangement brings the axles above the 85 level of the lower edges of the side sills.

A bottom plate, E, is placed between the side sills, at the left hand end of the car and extends from one side sill to the other from the rear end sill forward at the level of the 90 lower edges of the side sills to a line approximately midway between said end sill and the rear axle, C. Thence said plate extends forward and obliquely upward to or nearly to the rear axle. Along each side edge, said 95 plate has an upward-directed flange, E¹, which bears against the adjacent side rails and is secured thereto by bolts.

The middle floor plate, F, extends below 100 and rearward of the rear axle, C, and along the lower edge of the side sills to a point between the two axles, and then said plate extends obliquely upward and forward to or nearly to the upper face of the forward axle, C. At each side edge, the plate, F, has an 105 upward-directed flange, F¹, which bears against the adjacent inner face of the side sill and is secured to said sill by bolts or rivets. Along its rear edge rearward of the rear axle, said plate has an upward-directed 110 flange, F², which rises to or nearly to the bottom plate, E.

A front bottom plate, G, is placed between the side sills and extends from behind the forward axle, C, downward and forward below said axle and upward and across the 5 rear part of the forward end sill. Along the inner face of each side sill said plate has an upward-directed flange, G¹, bearing against said face and secured thereto by bolts or rivets. Along its rear edge and 10 rearward of the forward axle, said plate has an upward-directed flange, G², rising to or nearly to the plate, F.

A movable door, not shown, is to be placed above the forward end sill. Said door is to 15 be opened when the car is to be tilted forward for the discharge of the load.

It is to be understood that the slant of the inclined bottom sections relative to the horizontal plane of the car is to be such as 20 to allow all the coal to slide from the car when the car is tilted forward on the tipple. In this connection we must take into consideration the slant at which the car is placed by the tipple.

25 There are lateral horizontal extensions of the bottom. To the outer faces of the side sills, B, are applied the upright arms of brackets, H, by means of bolts or rivets, H¹. Said brackets constitute supporting members. The other arms of said brackets extend horizontally away from the sills. Bottom plates, H², rest on said arms of the brackets and extend from the side sills outward to the outer limits of the car body. 30 Said plates are secured to said brackets by bolts or rivets, H³.

At each of the four wheels, W, there is 35 as opening in the adjacent bottom plate, H², to make room for the upper part of the wheel, that part of the wheel extending above the plane of said bottom plates. At 40 each wheel, a metal housing, H⁴, extends over the wheel and has base flanges, H⁵, which rest on and are riveted to the adjacent bottom plate. The rear part of each housing is extended rearward to incline or 45 slant its upper face to allow coal or other material to slide forward over the housing when the car is tilted forward for the forward discharge of its load. Thus the forward part may be concentric to the wheel, while the rear part of the housing is given the slant or incline above mentioned.

Upright side walls, I, have flanges, I¹, 50 resting on and riveted or bolted to the adjacent bottom plate. The rear end of the car has a fixed end wall, I². At the forward end of the car the door is to be regarded as an end wall. While it is closed, it serves as 55 such. While the drawings show the auxiliary

bottom plates, H², at the elevation of the upper edges of the side sills, it is to be noted that the horizontal arms of the brackets, H, may be placed lower for correspondingly lowering these bottom plates. In some situations, placing these side plates lower than is shown in the drawings would make their outer margins liable to contact with objects lying beside the track. Where the track can be kept clear in this respect, the 65 bottom plates may be placed lower than shown.

Attention is again asked to the desirability of placing a load close to the track rails, in order that the car may be adapted to carry 75 a maximum load where there is low head room and in order that the car may have greater stability on the track.

Placing the bottom plates low between the side sills, as herein described, and placing 80 the horizontal auxiliary bottom plates, H², outside the side sills will place the load as close to the track rails as operating conditions permit.

The manner of applying the bottom 85 plates, H², affords ample stability for those plates and for the wheel housings, H⁴.

I claim as my invention:

1. In a car of the kind described, the combination of a frame comprising end sills and 90 side sills, axles applied to the side sills above the lower edges of said sills, a stationary bottom structure extending below the top of the axles and from one side sill to the other, supporting members extending outward from the side sills, auxiliary bottom sections resting on said supporting members and having wheel openings, housings seated over said openings and slanting rearward to permit forward sliding of coal when the car 100 is tilted forward for discharge, and upright walls, substantially as described.

2. In a car of the kind described, the combination of a frame comprising end sills and 105 side sills, axles applied to the side sills, a bottom between the side sills, an auxiliary bottom section at each side of the frame, wheels surrounding the axles and extending upward through openings in the auxiliary bottom sections, housings seated over said 110 openings and slanting rearward to permit forward sliding of coal when the car is tilted forward, and walls rising from the auxiliary bottom sections, substantially as described.

In testimony whereof I have signed my name, this 6th day of May, in the year one thousand nine hundred and twenty-four.

HUGH W. SANFORD.
